STOCK CONTROLLER

Robert E. Bowen, Plymouth, N. C., assignor to
 North Carolina Pulp Company, Plymouth, N. C.,
 a corporation of Delaware

Application January 26, 1946, Serial No. 643,500

12 Claims. (Cl. 137—78)

1

This invention relates to improvements in stock controllers.

Heretofore, in the manufacture of paper, the stock from the storage tanks has been pumped to the dewatering chest and the operators have attempted to control the consistency by means based largely upon observation. The best that the average operator can do is to control the consistency within a 1% range. At a 5% consistency, a chest may hold 4,000 pounds of bone-dry pulp. At a 4.5% consistency, the same chest will hold 3,600 pounds of bone-dry pulp, and at a 5.5% consistency, the same chest will hold 4,400 pounds of bone-dry pulp. It is thus apparent that with a 1% range in the control of the stock consistency, it is possible to get a variation of between 3,600 pounds and 4,400 pounds of bone-dry pulp, giving a possible error of 22.2% in the amount of bone-dry pulp in the chest. With most prior methods of control, the usual method is to bring all of the stock to the place where the consistency is to be observed at a consistency which is too great, and to regulate its consistency merely by adding water. This is an unsatisfactory method. The lack of proper control has, in the past, given a wide variation in paper tests and the operators found it nearly impossible to control the color on some runs of paper.

It is a general object of the present invention to provide apparatus which is capable of taking stock at any consistency between the lowest practical consistency and any higher consistency that can be pumped, and either take out water or add water automatically in order to give a uniform flow of stock at a uniform consistency.

A further object of the invention is to provide a stock controller which is so constructed as to maintain a proper level in the intermediate chest, that is, the chest in which the consistency regulator operates, whereby there is always ample stock of uniform consistency adjacent the rotary stock measuring valve at the outlet end, so that the chambers of said stock measuring device will always deliver the same amount and consistency of stock.

A more specific object of the invention is to provide a device as above described, wherein not only the inflow of dilution water in the consistency regulator chamber is controlled, but also the outflow of water from the dewatering chamber through the dewatering cylinder. As a result, stock which is too thin has some of the water removed and stock which is too thick has water added thereto, and the consistency is controlled within narrow limits.

2

A further, more specific object of the invention is to provide an apparatus as above described, which includes a float responsive to the level of the stock in the consistency regulator chamber and operably connected with the inlet valve leading to the dewatering chamber, for controlling the admission of stock to said dewatering chamber.

With the above and other objects in view, the invention consists of the improved stock controller, and all its parts and combinations, as set forth in the claims, and all equivalents thereof.

In the accompanying drawing, illustrating one complete embodiment of the preferred form of the invention, in which the same reference numerals designate the same parts in all of the views:

Fig. 1 is a side elevational view of the improved stock controller, parts being broken away and shown in vertical section;

Fig. 2 is a plan view of the apparatus illustrated in Fig. 1;

Fig. 3 is a fragmentary plan view illustrating the equipment mounted above the consistency regulator chamber;

Fig. 4 is a fragmentary sectional view taken on line 4—4 of Fig. 3, part of the motor being shown in full;

Fig. 5 is a fragmentary side elevational view illustrating the automatic valve for controlling the in-flow of stock to the dewatering chest, the connections of the valve with the pilot valve being also illustrated; and

Fig. 6 is a longitudinal sectional view taken on line 6—6 of Fig. 3.

Referring more particularly to the drawings, the numeral 10 designates a suitable tank or chest preferably formed with a widened inlet end 11. Located within the widened portion 11 is a dewatering compartment 12, containing a dewatering cylinder 13 of any standard variety such as is commonly used in savealls, thickeners, or paper machine vats. The cylinder has the usual screened periphery and there is an outlet pipe 14 through which water removed from the stock in the dewatering compartment by the dewatering cylinder can be drained. Stock pumped or otherwise caused to flow from the stock chest is adapted to enter the dewatering compartment 12 through a pipe 15, and the admission of stock is controlled by a stock inlet valve 16. There is also a secondary stock pipe 17 controlled by a valve 18 for admitting secondary stock into the dewatering compartment. Located ahead of the dewatering compartment

and projecting downwardly from the top of the tank, is a partition 19 which terminates a substantial distance above the bottom of the tank. Forwardly of the partition 19 is a consistency regulator chamber 20. A partition 21 extending upwardly from the bottom of the tank and terminating a substantial distance below the top of the tank separates the consistency regulator chamber proper from a chamber portion 22. A partition 23, extending downwardly from the top of the tank supports an arcuate plate 24. Near the bottom of the tank and positioned opposite to the plate 24, is an arcuate plate 25. A rotatable outlet valve 26, having four compartments as illustrated, is adapted to deliver stock from the chamber portion 22, in measured batches to the outlet chamber 27. The outlet valve is rotated through the use of a variable speed, motor driven speed reducer 28 of any well known type. The outlet chamber has a discharge pipe 27' usually leading to the No. 1 machine in the beater room.

A float 29, within the chamber portion 22 operates to raise or lower a rod 30 and the latter actuates a pilot valve 31 preferably of the type illustrated in Fig. 5. It is preferred to utilize hydraulic means for transmitting motion from the pilot valve 31 to the stock inlet valve 16. However, any other suitable mechanism may be substituted for hydraulic. For example, the controls may be pneumatic or electromagnetic. Where an hydraulic control system is employed, hydraulic fluid under pressure, such as water, enters the pilot valve 31 through an inlet 32 leading from a suitable source. If the float 29 is lowered to lower the rod 30, this indicates the need for additional stock to maintain a desired level, and the pilot 31 will cause hydraulic fluid to flow through the line 33 into the lower end of an hydraulic actuating cylinder 34 (see Fig. 5). This will cause movement of a piston 35, piston rod 36, and rack 37. Rack 37 may act through a gear segment 38 to cause rotation of a plug within the valve 16 and opening of the valve to admit additional stock. Hydraulic fluid from above the piston 35, within the cylinder 34, is exhausted through the line 39 leading back to the pilot valve. Where the fluid is water, the valve arrangement is such as to discharge the water out of a bleeder line 40.

When enough stock has been admitted to raise the level in the compartment 22, the float 29 will rise and cause upward movement of the rod 30. This will cause a reversal of flow to take place within the pilot valve 31 so that the hydraulic fluid under pressure will now flow through the line 39 to the top side of the piston 35 within the cylinder 34 to cause a closing movement of the valve 16. During such action, the fluid from below the piston 35 will be exhausted through the line 33 into the pilot valve and out of the bleeder line 42.

Above the compartment 20 is a platform 43 which supports the consistency regulator mechanism proper. Consistency regulators are commonly employed in the paper making art. It is preferred to utilize a De Zurik consistency regulator, but other consistency regulators now on the market may be employed. In the construction illustrated, and referring more particularly to Figs. 3 and 4, there is a bearing 44 rigidly connected to the platform 43. Rotatable in the bearing 44 is a vertical shaft 45 which supports feeler blades 46 at its lower end. The shaft 45 is driven by an electric motor 41. Connected to the lower end of the motor is an inverted cup-shaped member 47 housing a bearing set 48. The ar-

angement is such, that under certain conditions of operation, the motor, together with the member 47, may turn relative to the base bearing 44. Connected to the rotatable portion 47 and projecting therefrom is an arm 49. A spring 50 is connected at one end to the arm 49 as is illustrated in Fig. 3 and at its other end to the movable end of an adjusting bolt 51. Manipulation of a wing nut 52 will cause a change in the tension of the spring 50.

Outwardly of the spring 50 are oppositely disposed stop bolts 53 and 54 (see Fig. 3), which are threaded in lugs projecting from the platform 43. These bolts are preferably adjusted to allow a movement of the arm 49 of about $\frac{1}{8}$ of an inch.

Supported on the platform 43 on one side of the movable arm 49 is a pilot valve 55 of a standard four-way type. Where an hydraulic operating system is used this valve may be the same as the valve 31. Hydraulic fluid such as water under pressure from a source may flow into the pilot valve through a line 56. When the valve is in one position, that is, when the arm 49 is contacting the stop bolt 54, the operating plunger 57 of the pilot valve is maintained in a position to permit fluid under pressure to flow through the line 58 and into the end of an hydraulic cylinder 59 to actuate a piston 60 and cause a plunger 61 to be moved to such a position as to cut off the flow of water from the inlet pipe 62 through the pipe portion 63 and through the valve fitting 64 into the dilution pipe 65 which discharges water into the stock to add additional water thereto.

The plunger of the pilot valve 55 may be connected to the arm 49 by a small stiff spring 66 to keep the strain off of the pilot valve. When the arm 49 is in a reverse position, that is, in contact with the stop bolt 53, then the plunger 57 of the pilot valve 55 will be pulled outwardly to reverse the position of the valve and cause hydraulic fluid under pressure to flow through the line 67 and cause opening of the valve 64 and a flow of water through the pipe 65 into the stock.

Also connected with the water pipe 62 may be a branch pipe 68 into which the flow of water is controlled by a manual valve 69. The pipe 68 leads to a horizontal shower pipe 70 over the dewatering compartment.

Supported on the platform 43 on the opposite side of the arm 49 is another pilot valve 71 which operates the same as pilot valve 55 and the same as the pilot valve 31. The plunger 72 of this valve is connected by a stiff spring 73 with the arm 49. When the arm 49 is in contact with the stop 54, with the flow of water to the dilution pipe 65 cut off, then hydraulic fluid from the source pipe 74 leading to the pilot valve 71 will flow through the line 75 leading to one side of an operating cylinder 76 to cause movement of a piston rod 77 connected with a rack 78 in a direction to open a valve 79 connected with the drain pipe 84 from the dewatering cylinder. When the valve 79 is in opened condition, water is allowed to drain out of the dewatering cylinder 73 to remove surplus water from the stock. The valve 79 and operating mechanism may be the same as the valve 16 shown in Fig. 5.

When the arm 49 is in contact with the stop bolt 54, then the pilot valve 71 will be in a reverse position to cause flow of hydraulic fluid through the line 80 to the opposite side of cylinder 76 and cause closing of the valve 79. It is thus apparent that, when the dilution valve 75 is open to allow entry of water through the

dilution pipe 65, that the dewatering cylinder drain valve 79 is always closed and vice-versa.

Operation

Moving stock from the stock chest enters the dewatering compartment 12 through the inlet pipe 15 under control of the automatic valve 16. The amount of stock entering is under control of the pilot valve 31 and the latter is operated by the float 29. The arrangement, of course, is such that a constant level is maintained in the chamber portions 20 and 22.

Water which is in the stock in the dewatering chamber 12 will flow through the perforations of the wire of the dewatering cylinder 13. The amount or quantity of this water which leaves the stock is controlled by the amount of water which is permitted to flow out of the drain pipe 14 by the automatic valve 79. This valve is under the control of the pilot valve 71 as heretofore explained.

The amount of water which flows into the stock through the dilution pipe 65 is controlled by the dilution valve 64 under the control of the pilot 55.

As the stock flows out of the dewatering compartment 12, beneath the partition 19, it is compelled by the partition 21 to flow upwardly through the feeler blades 46 before it can pass into the compartment section 22. The resistance to rotation of the feeler blades, because of the passage of stock therethrough, is transmitted to the tension spring 50 connected to the arm 49. If the stock is relatively thin, there will be less resistance to rotation of the feeler blades 46 by the motor 41 and this resistance will be less than the tension of the spring 50. Consequently, the spring 50 will pull the arm 49 toward the stop bolt 54. This will cause the pilot valve 55 to shut off the supply of dilution water through the pipe 65 and will cause the pilot valve 71 to act to open the drain valve 79 and permit removal of water from the stock of the dewatering compartment.

If, after water is removed, the resistance to rotation of the feeler blades 46 increases due to thickening of the stock, then the motor 41 will tend to want to rotate around the fixed bearing 44 instead of imparting additional rotation of the shaft 45. This will cause movement of the arm 49 with the rotating motor to the position shown in Fig. 3, while stretching the spring 50. In other words, the resistance to rotation of the feeler blades imparted by the stock causes the motor to want to rotate independently on its base with a force which is greater than the tension of the spring 50. This movement will cause the plunger 57 of the pilot valve 55 to be moved to position to cause actuation of the valve 64 in a valve opening direction to permit water from the supply source 62 to flow through the dilution pipe 65 and into the stock to thin out the same. At the same time the pilot valve 71 will operate to shut the drain valve 79 and prevent removal of further water by the dewatering cylinder. In actual operation, one or the other of the pilot valves 55 or 71 will always be operating to either cause dilution of the stock or removal of water through the pipe 14. Thus, only stock at the proper consistency will flow to the rotary measuring valve 26 and the level in the chamber portion 22 will always be kept constant by the float 29. Inasmuch as the rotary valve 26 has an adjustable, variable speed drive, this can be set to deliver stock into the discharge chamber 27 at

any desired rate and will give the correct number of pounds of bone-dry stock, so that the proper quantity of chemicals can be added to give a uniform furnish to the paper machine. It is to be noted that the dewatering is performed as close to the consistency regulator as possible. This overcomes any pumping difficulties and enables the use of the feeler motor to control the amount of water that is removed from the stock.

As before mentioned, instead of having the valves 16, 64 and 79 hydraulically operated through the use of hydraulic fluid such as water flowing through the pilot valves 31, 55 and 71, it is possible to use any other suitable type of valve actuation or any other type of suitable valve actuating medium. The particular valves, pilot valves, cylinders, and consistency regulator may also be varied as long as the arrangement of parts is such as to accomplish the purposes of the present invention. The dewatering cylinder may be used with vacuum pumps if desired, to increase its capacity.

Various other changes and modifications may be made without departing from the spirit of the invention, and all of such changes are contemplated as may come within the scope of the claims.

What I claim is:

1. A paper machine stock controller comprising a tank having a dewatering chamber and having a discharge outlet, means for delivering paper making stock into said dewatering chamber, means including a drain pipe for removing water from stock in said dewatering chamber, a dewatering valve controlling the flow of removed water out of said drain pipe, means for delivering dilution water into the stock in said tank, a valve for controlling the flow of dilution water, and consistency responsive means for controlling said valves located in a portion of said tank where the stock is substantially at final discharge consistency to maintain the consistency of the stock substantially constant.

2. A paper machine stock controller comprising a tank having a dewatering chamber and having a discharge outlet, means for delivering paper making stock into said dewatering chamber, means including a drain pipe for removing water from stock in said dewatering chamber, a dewatering valve controlling the flow of removed water out of said drain pipe, means for delivering dilution water into the stock in said tank, a valve for controlling the flow of dilution water, and consistency responsive means for causing opening of said dewatering valve and simultaneous closing of said dilution valve and vice versa located in a portion of said tank where the stock is substantially at final discharge consistency to maintain the consistency of the stock substantially constant.

3. A paper machine stock controller comprising a tank having a dewatering chamber, means for delivering paper making stock into said dewatering chamber, means including a drain pipe for removing water from stock in said dewatering chamber, a dewatering valve controlling the flow of removed water out of said drain pipe, means for delivering dilution water into the stock in said tank, a valve for controlling the flow of dilution water, a motor propelled rotary feeler in said stock, and means responsive to the amount of resistance to rotation of the feeler imposed by the stock in a portion of said tank for controlling said valves to maintain the consistency of the stock substantially constant.

4. A paper machine stock controller comprising a tank having a dewatering chamber and having a discharge outlet, means for delivering paper making stock into said dewatering chamber, a dewatering cylinder in said dewatering chamber, a drain pipe extending from said dewatering cylinder, a dewatering valve controlling the flow of removed water out of said drain pipe, means for delivering dilution water into the stock, a valve for controlling the flow of dilution water, and consistency responsive means for controlling said valves located in a portion of said tank where the stock is substantially at final discharge consistency to maintain the consistency of said stock substantially constant.

5. A paper machine stock controller comprising an elongated tank having a dewatering chamber at one end and having a stock regulating chamber beyond said dewatering chamber and having a discharge outlet, means for delivering paper making stock into said dewatering chamber to flow longitudinally through the tank, a dewatering cylinder in said dewatering chamber, means including a drain pipe for removing water from the dewatering cylinder, a dewatering valve controlling the flow of removed water out of said drain pipe, means for delivering dilution water into the stock after it has left the dewatering chamber and before it has passed through the regulating chamber, a valve for controlling the flow of dilution water, and consistency responsive means for controlling said valves located in a portion of said tank where the stock is substantially at final discharge consistency to maintain the consistency of said stock substantially constant.

6. A paper machine stock controller comprising a tank having a dewatering chamber, means for delivering papermaking stock into said dewatering chamber, means including a drain pipe for removing water from stock in said dewatering chamber, a dewatering valve controlling the flow of removed water out of said drain pipe, means for delivering dilution water into the stock in said tank, a valve for controlling the flow of dilution water, a movably supported regulator arm, yielding means normally urging said arm in one direction, means responsive to an increase in the consistency of the stock in a portion of said tank for moving said arm in the opposite direction against the tension of said yielding means, a valve operating pilot on one side of said arm having a part moved by the arm when the latter is moved in one direction, a valve operating pilot on the other side of said arm having a part moved by the arm when the latter is moved in the opposite direction, and connections between said valve operating pilots and said dewatering valve and dilution valve for causing opening of said dewatering valve and simultaneous closing of said dilution valve and vice versa to maintain the consistency of the stock substantially constant.

7. A paper machine stock controller comprising a tank having a dewatering chamber, means for delivering paper making stock into said dewatering chamber, means including a drain pipe for removing water from stock in said dewatering chamber, a dewatering valve controlling the flow of removed water out of said drain pipe, means for delivering dilution water into the stock in said tank, a valve for controlling the flow of dilution water, a movably supported regulator arm, yielding means normally urging said arm in one direction, means including a motor driven

feeler blade supported for rotation in the tank and responsive to an increase in the consistency of the stock in a portion of said tank for moving said arm in the opposite direction against the tension of said yielding means, a valve operating pilot on one side of said arm having a part moved by the arm when the latter is moved in one direction, a valve operating pilot on the other side of said arm having a part moved by the arm when the latter is moved in the opposite direction, and connections between said valve operating pilots and said dewatering valve and dilution valve for causing opening of said dewatering valve and simultaneous closing of said dilution valve and vice versa to maintain the consistency of the stock substantially constant.

8. A paper machine stock controller comprising a tank having a dewatering chamber and having a discharge outlet, means including an inlet pipe for delivering paper making stock into said dewatering chamber, a valve in said inlet pipe, means including a drain pipe for removing water from stock in said dewatering chamber, a dewatering valve controlling the flow of removed water out of said drain pipe, means for delivering dilution water into the stock, a valve for controlling the flow of dilution water, consistency responsive means for controlling said dilution valve and said dewatering valve located in a portion of said tank where the stock is substantially at final discharge consistency to maintain the consistency of said stock substantially constant, and means located in a portion of said tank where the stock is at substantially final discharge consistency and responsive to the level of stock in said portion of the tank for controlling said inlet pipe valve.

9. A paper machine stock controller comprising a tank having a dewatering chamber and having a discharge outlet, means for delivering paper making stock into said dewatering chamber, means including a drain pipe for removing water from stock in said dewatering chamber, a dewatering valve controlling the flow of removed water out of said drain pipe, means for delivering dilution water into the stock in said tank, a valve for controlling the flow of dilution water, consistency responsive means for controlling said valves located in advance of said discharge outlet and in a portion of said tank where the stock is substantially at final discharge consistency to maintain the consistency of said stock substantially constant, and a rotatable volume measuring discharge valve at said discharge outlet for discharging stock at a predetermined rate.

10. A paper machine stock controller comprising an elongated tank having a dewatering chamber and having a discharge outlet, means including an inlet pipe for delivering paper making stock into said dewatering chamber to flow longitudinally through said tank, a valve in said inlet pipe, means including a drain pipe for removing water from stock in said dewatering chamber, a dewatering valve controlling the flow of removed water out of said drain pipe, means for delivering dilution water into the stock, a valve for controlling the flow of dilution water, consistency responsive means for controlling said dewatering valve and said dilution valve located in advance of said discharge outlet and in a portion of said tank where the stock is substantially at final discharge consistency to maintain the consistency of said stock substantially constant, means located in a portion of said tank where

the stock is at substantially final discharge consistency and responsive to the level of stock in said portion of said tank for controlling said inlet pipe valve, and a rotatable volume measuring discharge valve at said discharge outlet for discharging stock at a predetermined rate.

11. A paper machine stock controller comprising an elongated tank having a dewatering chamber at one end and having a regulating chamber beyond said dewatering chamber and having a discharge outlet, means including an inlet pipe for delivering paper making stock into said dewatering chamber to flow longitudinally through said tank, a valve for controlling the flow into the tank from said inlet pipe, a dewatering cylinder in said dewatering chamber, a drain pipe for removing water from said dewatering cylinder, a dewatering valve controlling the flow of removed water out of said drain pipe, means for delivering dilution water into the stock after it has left the dewatering cylinder and before it has passed through the regulating chamber, a valve for controlling the flow of dilution water, consistency responsive means for controlling said dewatering valve and said dilution valve located in a portion of said tank where the stock is substantially at final discharge consistency to maintain the consistency of said stock substantially constant, and means including a float located forwardly of said last mentioned means in a portion of said tank where the stock is at substantially final discharge consistency and responsive to the level of stock in said portion of the tank for controlling said inlet pipe valve.

12. A paper machine stock controller comprising an elongated tank having a dewatering chamber at one end and having a regulating chamber beyond said dewatering chamber and having a discharge outlet, means including an inlet pipe for delivering paper making stock into

said dewatering chamber to flow longitudinally through said tank, a valve for controlling the flow into the tank from said inlet pipe, a dewatering cylinder in said dewatering chamber, a drain pipe for removing water from said dewatering cylinder, a dewatering valve controlling the flow of removed water out of said drain pipe, means for delivering dilution water into the stock after it has left the dewatering cylinder and before it has passed through the regulating chamber, a valve for controlling the flow of dilution water, consistency responsive means for controlling said dewatering valve and said dilution valve located in advance of said discharge outlet and in a portion of said tank where the stock is substantially at final discharge consistency to maintain the consistency of said stock substantially constant, means including a float located forwardly of said last mentioned means in a portion of said tank where the stock is at substantially final discharge consistency and responsive to the level of stock in said portion of the tank for controlling said inlet pipe valve, and a rotatable volume measuring discharge valve at said discharge outlet and at the opposite end of the tank from the dewatering chamber.
